(57) **CLAIM**

The ornamental design for packaging with surface ornamentation, as shown and described.

DESCRIPTION

FIG. 1 is a perspective view of packaging with surface ornamentation of the present invention;
FIG. 2 is a front view thereof;
FIG. 3 is a rear view thereof;
FIG. 4 is a right view thereof;
FIG. 5 is a left view thereof;
FIG. 6 is a top view thereof;
FIG. 7 is a bottom view thereof;
FIG. 8 is a perspective view of a second environment thereof;
FIG. 9 is a rear view thereof;
FIG. 10 is a front view thereof;
FIG. 11 is a right view thereof;
FIG. 12 is a left view thereof;
FIG. 13 is a top view thereof; and,
FIG. 14 is a bottom view thereof.
The broken lines depict environmental subject matter only and form no part of the claimed design.
